UNITED STATES PATENT OFFICE

2,501,521

DRAFTING INSTRUMENT

William H. Howard, Niagara Falls, Ontario,
Canada

Application September 23, 1946, Serial No. 698,722

4 Claims. (Cl. 33—75)

1

This invention relates to new and useful improvements and structural refinements in drafting instruments, and the principal object of the invention is to provide a device of the character herein described, such as may be effectively and conveniently employed as an adjustable protractor, for the purpose of plotting angularly offset lines and for determining the angular deviation of existing lines and surfaces.

The further object of the invention is to provide a drafting instrument which, in addition to its use as above said forth, will also provide a generally useful accessory in the work of the draftsman.

Another object of the invention is to provide a drafting instrument which may be readily adapted for use in association with drafting machines.

An additional object of the invention is to provide a drafting instrument which is simple in construction and operation, and which will not easily become damaged.

With the above more important objects in view, and such other objects as may become apparent as this specification proceeds, the invention consists essentially of the arrangement and construction of parts as illustrated in the accompanying drawings, in which:

Figure 1 is a top plan view of the invention, and

Figure 2 is a cross sectional view taken substantially in the plane of the line 2—2 in Figure 1.

Referring now to the accompanying drawings in detail, the invention consists of a drafting instrument designated generally by the reference character 5, the same embodying in its construction a pair of plates 6 and 7, each formed from plates having the general configuration of a right-angled isosceles triangle.

The base 8 opposite the right-angled apex 9 of the plate 6 is formed with a semi-circular recess 11 having a center at point 10, while the right-angled apex portion of the plate from which plate 7 is made is relieved as at 12, the relieved portion of the plate being of a sector-like formation.

A transparent circular protractor 13 is positioned between the plates 6 and 7, and it will be noted that the arcuate edges 14 and 15 of the two plates respectively, are complementary to the circumferential edge of the protractor. It will be also observed that the protractor 13 as well as the plates 6 and 7 are disposed in a common plane.

The plate 6 is provided with a substantially 55

2

T-shaped bearing bracket 16 formed of translucent material, while the plate 7 is equipped with a superimposed translucent bracket 17. These brackets are secured to the respective plates by means of rivets 18, and the bracket 16 is offset as at 19 to provide a space for a portion of the bracket 17, as is best shown in Figure 2.

A pivot pin 20 is secured in the center of the protractor 13 and also engages both the bracket 16 and the bracket 17. In this manner, the plates 6 and 7 are pivotally connected to the protractor 13, so that the center 10 is coincident with the right-angled apex of the plate from which plate 7 is made and with the center of the protractor 13.

Means are provided for releasably locking the plates 6 and 7 in a predetermined position with respect to the protractor 13, the same assuming the form of a screw 22 associated with each of the said plates. For the purpose of accommodating the screw head, each of said plates is provided adjacent the arcuate edge (14 or 15) thereof with a substantially semi-circular recess 23, while the protractor 13 is formed adjacent its circumferential edge with a marginal undercut 24. The screws 22 extend through the brackets 16 and 17, and carry suitable knurled adjusting nuts 25.

The protractor 13 is equipped, on the underside thereof, with a suitably graduated scale 26, and the underside of each of the plates 6 and 7 is inscribed with an index line 27. It should be also noted that one-half the length of the base 8 is equal to each of the two equal sides 28 of the plate 7.

When the invention is placed in use, the advantages of the two indexes 27 will be readily appreciated in association with the protractor scale 26, since it is not necessary to add or subtract complementary and supplemental angles, as has been the conventional practice in determining angular relationships.

It is believed that the application and use of the invention, as well as the advantages resulting therefrom, will be readily apparent to those skilled in the art and accordingly, further description thereof at this point is considered unnecessary.

While in the foregoing there has been shown and described the preferred embodiment of this invention it is to be understood that minor changes in the details of construction, combination and arrangement of parts may be resorted to without departing from the spirit and scope of the invention as claimed.

What I claim as my invention is:

1. A drafting instrument comprising a first plate and second plate complementary thereto, said first plate having two sides of equal length and a substantially longer connected side, a medial arcuate recess in said longer side, said second plate having three straight sides and a concave side, a transparent bearing bracket superimposed on said first plate and extending over said recess, a companion transparent bearing bracket secured to said second plate and extending outwardly from the concave side, a pivot element connected to said brackets, a circular protractor mounted on said pivot element and disposed in said concaved side and recessed side of the second and first plates and in a common plane with said plates and means for releasably locking said plates in adjusted interrelated positions around the circumference of the protractor.

2. A drafting instrument comprising a first plate and a second plate associated therewith, said first plate having a base and a pair of opposed sides of equal length connected to the opposite ends of said base, said sides being converged inwardly and joined at a common point, said base having a medial arcuate recess, said second plate having a major end constituting a base and a pair of equal sides joined at one end to the opposite ends of the base and converging inwardly therefrom, a concave minor end connected to the opposite ends of the sides, a transparent bearing bracket secured to the upper surface of said first plate and extending forwardly of the medial portion of the base, a companion transparent bearing bracket fixed on the upper surface of said second plate adjacent the medial portion of the base and extending forwardly of the concave minor end, a pivot element connected to the extended ends of said brackets, a circular transparent protractor mounted at its center on the pivot element, said protractor be-

ing disposed in the concave minor end of the second plate and in the recess in the base of the first plate and in a common plane with the first and second plate, and means for releasably locking said plates in adjusted interrelated positions around the circumference of the protractor.

5. The combination of claim 2, wherein said plates are each provided with an index line located on a line intersecting the medial portion of the bases.

10. The combination of claim 2, wherein said locking means includes a recess formed in the underside of each of the plates, a diametrically reduced bore vertically disposed through said plates from the recess, a threaded locking pin seated in said recesses and extended through the plates and the brackets adjacent the protractor, a complementary internally threaded locking nut received on said pins.

15. WILLIAM H. HOWARD.
